ISLAND TYPE FOUNDATION STRUCTURE

George P. Wiedman, North Tonawanda, N. Y.

Application March 2, 1950, Serial No. 147,186

2 Claims. (Cl. 94—1)

1

This invention relates to structures and more particularly to an improved island type foundation structure.

Matter disclosed but not claimed in this application is disclosed and claimed in my copending application, Serial No. 147,187 of March 2, 1950, entitled "Curb Member" of which the present application is a continuation-in-part.

By "island type foundation structure" is meant a raised base structure which is upstanding from the surrounding ground level or surface. Such island type foundation structures are commonly used for many different purposes. For example, they are used in gasoline stations to support apparatus for dispensing gasoline or other materials and display racks of various types; to support cashier booths at the entrance to bridges, drive-in theaters and the like; or are used as raised platforms on which persons wait to board public conveyances or onto which they alight from such conveyances. Heretofore it has been usual to construct such island type foundation structures of solid concrete. This required digging, setting up forms to define the perimetrical form desired, thereafter pouring concrete into the forms, allowing the concrete to harden and then removing the forms. Such solid concrete block type island foundation structures took a considerable time to install and hence were expensive; were heavy and therefore prone to settle and crack; and had the disadvantage of the concrete edges spalling off or being broken off by the wheels of vehicles striking the same thereby producing an unsightly structure which could not be repaired readily. Moreover, vehicles which were driven carelessly against the island were known to climb or ride up over the edge of the concrete foundation structure and damage the superstructure arranged thereon.

It is therefore the objects of the invention to provide an island type foundation structure of improved construction which can be easily and quickly installed; which can be adjusted or taken up if desired; which is relatively light in weight but yet sturdy and resistive to abusive treatment; which tends to prevent vehicle wheels from climbing its side walls and in doing so does not damage the tires thereby avoiding damage to the vehicle and to the superstructure on the foundation structure; which permits of access to the interior of the foundation structure for maintenance of equipment supported on the foundation structure; which retains its original form and is not subject to unsightly deterioration; and which is relatively inexpensive.

2

Other objects and advantages of the invention will be apparent from the following detailed description and accompanying drawings wherein:

Fig. 1 is a perspective view of an island type foundation structure embodying the present invention and showing the same adapted for supporting gasoline pumps and light poles represented by broken lines.

Fig. 2 is a plan view of the foundation structure shown in Fig. 1 but with the deck plates removed.

Figs. 3 and 4 are respectively side and end elevational views of the foundation structure shown in Fig. 1.

Fig. 5 is an elevational view of the bottom of the foundation structure shown in Fig. 2.

Fig. 6 is an enlarged vertical transverse sectional view of the foundation structure taken along line 6—6 of Fig. 2 but showing the deck plate in position and also showing the manner of mounting and anchoring the structure on the ground.

Fig. 7 is an enlarged fragmentary vertical longitudinal sectional view taken along line 7—7 of Fig. 1 and showing the details of mounting the light pole on the foundation structure.

Fig. 8 is a fragmentary vertical transverse sectional view thereof taken along line 8—8 of Fig. 7.

The island type foundation structure forming the subject of the present invention is preferably fabricated of sheet metal or plate stock, and is shown as comprising a pair of side sections 10, 10 and end sections 11, 11. The side sections 10, 10 are arranged parallel to each other in spaced relation and are shown as of the same length, these side sections providing longitudinal frame members. The end sections 11, 11 are identical in construction and are arranged at opposite ends of the side members 10, 10. In view of the identical constructions of the pairs of side and end sections 10 and 11 respectively, the same reference numerals will be used to identify similar parts in each corresponding pair of sections.

Each side section 10 comprises a metal base plate 12 of elongated rectangular shape as best shown in Fig. 5. A hollow inverted generally V-shaped upstanding member having diverging legs is arranged on the upper surface of this base plate 12 and comprises inner and outer walls or ribs 13 and 14 respectively conjoined at their upper ends as indicated at 15 and separated at their lower ends adjacent the base plate 12. This upstanding member is preferably formed by bending an elongated rectangular plate into the

3

inverted V-shape shown. The integral connecting web 15 at the apex of the conjoined walls 13 and 14 is preferably rounded as shown.

The lower edges of the walls 13 and 14 are each connected to the base plate 12 in any suitable manner and as shown preferably by weldments 16. These weldments 16 are preferably arranged at spaced intervals along the joint between the base plate 12 and the lower edge of the corresponding side wall 13 or 14 on the outside of these walls thereby leaving narrow slits 18 between adjacent weldments. These narrow elongated slits 18 provide vents and drainage openings for the interior of the upstanding member.

The side walls 13 and 14 and the central portion of the base plate 12 therefore form in cross section substantially an equilateral triangular metal member which is of great strength and self-reinforcing although of relatively light weight. While the base plate and upstanding member are shown as being formed of sheet metal or plate stock of the same thickness, this is not necessary and either can be thicker or thinner than the other within the operative limits of providing a sufficiently rigid structure.

As shown, the base plate 12 extends outwardly beyond the lower edge of the outer wall 14 to provide an attaching outer flange 19. The opposite longitudinal marginal portion of the base plate 12 similarly provides an inner attaching flange 20 which extends laterally outwardly from the lower edge of the inner wall 13.

The end sections 11 can be either rounded or of the pointed or wedge shape shown. As shown in Fig. 5, each end section includes a base plate 21 of generally triangular shape. The inner transverse edge of this base plate 21 is preferably welded to the abutting end edges of the base plates 12 of the side sections 10, 10. The base plates 12 and 21 are coplanar. Each end section 11 also includes an upstanding member having inner and outer walls 131 and 141 respectively, similar in form and construction to the walls 13 and 14 of the side sections 10 and are preferably welded to the base plate 21 in the same manner as for the walls 13 and 14 of the side sections 10. The upstanding member of each end section having the pointed shape shown is preferably formed by arranging two straight inverted trough or V-shaped sections at an angle one to the other so that their corresponding ends meet and welding these ends together along the line 22. This line of welding 22 extends along the joint between the two parts of the outer wall 141, over the crest and thence along the joint between the two parts of the inner wall 131. A similar line of welding 23 connects the walls 13 and 14 of each side section 10 at each end with the adjacent ends of the walls 131 and 141 of the end sections 11.

The base plate 21 for each end section 11 extends laterally outwardly beyond the lower edge of the outer wall 141 to provide an outer attaching flange 24.

The structure so formed provides a rigid perimetrical base plate from which rises a continuous perimetrical upstanding frame member, the latter in the form of an inverted V-shaped channel secured to the base plate. Such a rigid unitary structure can be anchored to the ground as by the spikes or anchor pins 25 shown in Fig. 6. These spikes or anchor pins 25 pass through a series of spaced holes 26 in the outer flanges 19 and 24 and also provided in the inner flanges 75

4

20 of the side sections 10. If desired either the outer flanges 19 or 24 or the inner flanges 20 can be eliminated so that the spikes or anchor pins 25 are either entirely on the inside or outside of the upstanding member.

When installing the aforesaid structure, the supporting foundation or ground 28 is flattened as shown in Fig. 6, the structure placed thereon and the spikes or anchor pins 25 driven into such foundation or ground. No fabrication on the job is required and installation is rapid and easy. If desired a layer 29 of surfacing material such as asphalt can be run up to the outer walls 14 and 141 to cover the outer attaching flanges 19 and 24 and also the heads of the spikes or anchor pins 25, as shown in Fig. 6. It will be seen that the structure has a relatively steep upwardly and inwardly slanting outer wall on all sides which has been found to be highly effective in preventing vehicle wheels from climbing over this wall.

Any suitable type of platform desired can be arranged on the rigid unitary structure so far described. If desired, even dirt, concrete, asphalt or the like can be used to fill in the cavity formed by the inner walls 13 and 131 of the foundation structure and this may be suitable for some uses.

However, for use as an island type foundation structure for supporting gasoline pumps and light poles, as illustrated in the drawings, it is preferred to leave the cavity formed by the inner walls of the continuous perimetrical upstanding member unfilled and covered by a deck. As shown, for this purpose, a narrow metal strip or flange 30 is arranged on the inner walls 13 and 131 near the upper edges thereof, this flange 30 preferably extending continuously along the walls parallel to the upper edges thereof and being welded to these walls. A central rectangular deck plate 31 and two triangularly shaped end deck plates 32 are arranged on the flange 30 and suitably connected thereto as by a series of screws 33 extending through holes in these deck plates and received in registered threaded holes 34 provided in the flange 30. The meeting ends of the end and central deck plates are supported by a transverse strut 37 extending between each corresponding pair of inner wall parts 131 of the end sections 11, the upper surface of the struts 37 being flush with the upper surface of the flange 30. These struts are also provided with threaded holes 34' to receive deck plate attaching screws 33'.

Referring to Fig. 1, a gasoline pump G with light pole P arranged adjacent the inner side thereof are represented as being mounted on the island type foundation structure adjacent each end thereof. Each pump G is shown as resting on the central deck plate 31 and covering an opening 35 therein through which the fluid and electrical conduits for the corresponding pump extend. In order to reinforce the deck plate 31 immediately under the pump G, a pair of transverse members 36 are arranged across and connected to the side sections 10 on opposite sides of the corresponding opening 35. As shown in Fig. 6, each transverse member 36 is in the form of an inverted channel having its web engaging the bottom of the central deck plate 31 and having each end offset downwardly as indicated at 38 so that the web at the extreme end portion extends under and supports the flange 30. The transverse members 36 are shown as having their ends welded to the corresponding inner walls 13

of the side sections 10. In this manner, the flat central deck plate 31 rests on the transverse members 36 and along opposite marginal sides also on the flange 30. As well as providing a reinforced supporting base for the pump G, the transverse members also serve to strengthen the upstanding side members of the foundation structure.

Each light pole P is shown as supported on the foundation structure in the following manner. An inverted channel shaped transverse member 40 similar to the members 36 is welded at its opposite ends to the inner walls 13 so that the web of the member 40 engages the bottom of the central deck plate 31 as shown in Figs. 7 and 8. The web of this member 40 midway of its ends is provided with a hole 41 adapted to receive the light pole P. A centering flange plate 42 is arranged on the upper surface of the deck plate 31 and connected thereto by a series of screws 43. The centering flange plate 42 and deck plate are provided with holes registering with the hole 41 in the member 40, the hole in the flange plate closely fitting the periphery of the light pole and by adjusting the position of this plate the light pole can be centered so as to assume an upright position.

The lower end of the light pole P is received in a short sleeve 45 welded to a base plate 46. This sleeve 45 is preferably internally threaded so that the threaded lower end of the light pole can be screwed into the sleeve and thereby secured.

The base plate 46 is shown as arranged on the upper surface of the web of an upwardly opening channel shaped transverse member 48. Bolts 49 connect the base plate 46 to the member 48. This member 48 is arranged under and in line with the corresponding upper transverse member 40 and adjacent the lower ends of the inner walls 13 of the side sections 10. The ends of member 48 are preferably welded to these inner walls 13. A vent hole 50 extends through the base plate 46 and the web of member 48 to vent the interior of the light pole which is usually in the form of a hollow pipe.

This construction provides a simple means for supporting the light poles P on the island type foundation structure.

From the foregoing it will be seen that the present invention provides an all metal island type foundation structure which can be rapidly

and easily installed as a unitary structure; which is exceedingly strong and lasting; which can be readily leveled if settling of the earth or other supporting foundation occurs and can also be readily taken up if desired; which has upwardly and inwardly inclining outer walls which tend to prevent vehicle wheels from climbing onto the top of the structure; which is relatively inexpensive; and which possesses other advantages.

I claim:

1. An all metal unitary island type foundation structure, comprising a base plate, a perimetrical upstanding member connected to one side of said base plate and being of inverted V-shaped form in cross section, a flange on the inner wall of said member adjacent the upper end thereof, and a deck member mounted on said flange and extending across the opening formed and surrounded by said perimetrical upstanding member, the outer surface of said deck member being substantially flush with the upper apex edge of said V-shaped member.
2. An all metal unitary island type foundation structure, comprising a base plate, a perimetrical upstanding member arranged on one side of said base plate and having upwardly convergent inner and outer walls conjoined at their upper ends and spaced apart adjacent said base plate, a flange on said inner wall adjacent the upper end thereof, reinforcing struts arranged between and connected to opposing portions of said inner wall, the upper surface of the intermediate portion of said reinforcing struts being substantially flush with the upper surface of said flange, and a deck plate member arranged on said upper surfaces of said flange and struts and being supported thereby.
